[57] CLAIM

The ornamental design for a combined wire snake with a locking clip, as shown and described.

DESCRIPTION

FIG. 1 is a front elevation view of a combined wire snake with the locking clip showing my new design;

FIG. 2 is a bottom plan view thereof;

FIG. 3 is a rear elevation thereof;

FIG. 4 is a left side elevation view thereof; and,

FIG. 5 is a right side elevation view thereof.

FIGS. 1-3 are shown fragmented to indicate indeterminate length.
